Des. 234,593
Patented Mar. 25, 1975

234,593

FISHING REEL OR SIMILAR ARTICLE

Morris E. Wood, Bronson, Mich., assignor to True
Temper Corporation, Cleveland, Ohio

Filed Dec. 6, 1973, Ser. No. 422,310

Term of patent 14 years

Int. Cl. D22—05

U.S. Cl. D22—25

FIG. 1

FIG. 2

FIG. 3

FIG. 4

FIG. 5

FIG. 6

FIG. 1 is a top plan view of a fishing reel or similar article showing my new design;

FIG. 2 is a side elevation thereof as viewed from below FIG. 1;

FIG. 3 is a bottom plan view thereof;

FIG. 4 is a side elevation thereof as viewed from above FIG. 1.

FIG. 5 is a front elevation thereof; and

FIG. 6 is a rear elevation thereof.

I claim:

The ornamental design for a fishing reel or similar article, as shown.
